PATENTED JUNE 9, 1908.

M. H. SULLIVAN.
LOCK FOR PISTON RINGS.
APPLICATION FILED AUG. 12, 1907.

UNITED STATES PATENT OFFICE.

MICHAEL H. SULLIVAN, OF POUGHKEEPSIE, NEW YORK.

LOCK FOR PISTON-RINGS.

No. 890,103.

Specification of Letters Patent.

Patented June 9, 1908.

Application filed August 12, 1907. Serial No. 388,224.

To all whom it may concern:

Be it known that I, MICHAEL H. SULLIVAN, a citizen of the United States, residing at Poughkeepsie, in the county of Dutchess and State of New York, have invented new and useful Improvements in Locks for Piston-Rings, of which the following is a specification.

This invention relates to piston packing rings and more particularly to means for locking the same so as to prevent the escape or passage of steam around the joint or ends of the rings where they are united.

The object of the invention is to provide a structure which will be simple, cheap and efficient and can be readily applied to pistons of internal explosion or gas engines.

It also has for its object to provide means for supporting what are known as carrying rings.

With these and other objects in view, the invention consists in the improved construction and novel arrangement of a piston and the packing rings therefor.

In the accompanying drawings, which illustrate the invention, Figure 1 is a broken end view of a piston for gas engines; Fig. 2 is a broken plan view of the same, showing the rings in position thereon; Fig. 3 is a broken perspective view of part of the end of a piston with the ends of a pressure ring and the lock therefor shown detached or separated; Fig. 4 is a transverse sectional view of a piston, showing a carrying ring; and also a pressure ring surrounding the carrying ring; and Fig. 5 is a detail sectional view of the rings, showing the means for connecting them together and holding them in position.

Referring more particularly to the drawings, which are for illustrative purposes only, and, therefore, are not drawn to any particular scale, 1 indicates the piston for the engine, which may be of any size and construction.

The periphery of the piston is provided with the usual annular recesses, 2 and 3, within which are seated rings, 4 and 5. The recesses, 3, are preferably formed in the usual manner with their walls continuous or unbroken, and the rings, 5, are preferably of the usual construction, with their ends adjacent to each other and so arranged as to overlap each other, and thereby provide an inclined or tortuous path for the passage of any gases that may be forced against the ring. The recess, 2, is provided with a recess, 6, in one of its walls for the reception of the lock, 7, which is preferably secured at

one end to the ring, 4, as by means of rivets through the perforations, 8.

As heretofore constructed, the ends of the lock fitted snugly in the ends of the recess, 6, but it has been found that when subjected to the terrific pressure which occurs at the time of explosion in an internal combustion or gas engine, that a portion of the gases is apt to be forced down in between the space, 6, 65 9, between the ends of the ring, and to escape at the ends of the recess, 6. To prevent this passage and escape of the gas, I provide two shoulders, or abutments, 10, adjacent to the ends of the recess, 6, and also to form a 70 sub-recess, 11, with which two shoulders, 12, at the ends of the lock, 7, are adapted to engage, the lock being provided with a recess, 13, adjacent to each end for the reception of the shoulders, 10. By constructing the 75 parts in this manner, when the lock, 7, is rigidly secured to the side of the ring, 4, with a projection, 14, thereon, fitting in a notch or recess, 15, in the ring, the lock is seated in the recess, 6, with the free end of the ring 4 80 resting flatwise against the free end of the lock, 7, as will be understood. With the parts assembled in this manner, it is evident that any gas that may enter the space, 9, will meet the shoulders, 10 and 12, and will be 85 thereby prevented from passing to the ends of the lock, 7, and escaping from the recess, 6, as is apt to occur without said shoulders. At the same time, the ring, 4, can act expansively so as to engage with the interior of the 90 cylinder in the same manner as though the lock, 7, were not present.

If desired, carrying rings, 16, may be seated in the bottom of the channels or grooves, 2 and 3, for supporting the outer or pressure rings, as shown in Fig. 4. With this construction, the rings 16 are formed in segments, with one or more projections, 17, upon the inner face thereof fitting in suitable recesses, 18, in the body of the piston. 100 Springs, 19, are preferably seated in the recesses, 18, for engaging with the projection, 17, or the rings, 16, and normally forcing the same outward against the interior of the pressure rings so as to assist in expanding or 105 forcing the latter outward so as to engage with the interior of the cylinder with as much pressure as desired. By constructing the rings 16 with their projections, 17, the rings are prevented from moving longitudinally within the annular recesses, and the pressure rings are preferably connected with

the carrying rings so as to be held against longitudinal movement within the recesses as by means of one or more pins, 20, which extend through a perforation in the pressure ring into a recess formed in the carrying rings, 16, and the projections, 17, thereon. The projections, 17, also assist in preventing the passage of any gases circumferentially around the grooves, 2 and 3, from the space between the ends of the inner rings to the space between the ends of the outer rings, thereby adding to the efficiency of the locking rings.

As above described, it is evident that my improved lock can be quickly applied to the pressure ring, whether the ring be of the ordinary rectangular area in cross section, or L-shaped, or any other area, thereby adapting the lock to any style of locking rings, the only requisite being that the recess in the piston be formed with the shoulder adjacent to the ends of its recess. It is also evident that the shoulders can be of other form than rectangular, as shown in the drawing, without departing from the spirit of the invention or destroying the efficiency of the structure. The use of the inner or carrying rings also assists materially in the efficiency of the construction, and can be easily applied by cutting the grooves or channels in the piston to a sufficient depth and providing the bottom of each with the desired recesses.

Having thus fully described my invention, what I claim as new, and desire to secure by Letters-Patent, is:

35. 1. The combination with a circumferentially grooved piston having a recess formed in one wall of said groove, of a pressure ring in said groove, and a lock for said ring adapted to fit in said recess, the bottom of the lock and of the recess being constructed with obstructions to prevent the passage of the gases.
2. The combination with a circumferentially grooved piston having a recess formed in one wall of the groove, and shoulders 45 formed in the bottom of the recess, a pressure ring in said groove, a lock secured thereto at one end, and adapted to fit in said recess, the inner edge of the lock being provided with shoulders and recesses to correspond 50 with the bottom of the recess in the piston.
3. The combination with a circumferentially grooved piston having a recess formed in one wall of said groove, the ends of said recess being provided with a shoulder and a 55 sub-recess, a pressure ring in said groove, a

locking plate rigidly secured at one end to one end of said ring and adapted to fit in the recess in the cylinder, the ends of said plate being each provided with a shoulder and a recess.

4. The combination with a circumferentially grooved piston having a recess formed in one wall of said groove, having the ends each provided with a rectangular shoulder and a sub-recess, an L-shaped pressure ring 60 for said groove having a notch in its inner edge of one end, and a locking plate rigidly secured to the notched end of said ring and provided with a projection for fitting in said notch, the ends of such plate being each provided with a projection and a recess for engaging with the shoulder and recessed ends of the recess in the piston.

5. The combination, with a piston provided with a circumferential groove, with recesses in its bottom and having a shouldered recess in one wall, an inner and an outer ring in said groove, the inner ring being provided with projections for fitting in the recess in the bottom of said groove, springs in said 75 recesses for forcing the inner ring outward, and a shouldered lock secured to one end of the outer ring and adapted to fit in said shouldered recess.

6. The combination with a piston provided with a circumferential groove and having recesses in the bottom of the groove and a shouldered recess in one wall of the groove, an inner and an outer ring in said groove, the inner ring being formed in sections and each 80 section provided with a projection for fitting in the recess of the bottom of the groove, said section and projection being recessed, a spring in each recess adapted to force the sections outwardly, the outer ring being perforated to register with the recess of the inner ring, pins through said perforations into said recesses, and a locking plate rigidly secured at one end to one end of the pressure ring and adapted to fit in the recesses in the wall of the 95 groove, each end of said plate being recessed to correspond with the shoulders in said recesses.

In testimony whereof I have signed my name to this specification in the presence of 105 two subscribing witnesses.

MICHAEL H. SULLIVAN.
